UNITED STATES PATENT OFFICE.

WALTER S. MCKEE, OF CHICAGO, ILLINOIS, ASSIGNOR TO AMERICAN MANGANESE STEEL COMPANY, OF CHICAGO, ILLINOIS, A CORPORATION OF MAINE.

BALL-MILL SHELL AND PLATE.

1,372,972.

Specification of Letters Patent. Patented Mar. 29, 1921.

Application filed August 1, 1919. Serial No. 314,674.

To all whom it may concern:

Be it known that I, WALTER S. MCKEE, a citizen of the United States, residing at Chicago, in the county of Cook and State 5 of Illinois, have invented certain new and useful Improvements in Ball-Mill Shells and Plates, of which the following is a specification.

This invention relates to ball mills, and 10 particularly to a cast metal shell for such mills and to comminuter or lining plates therefor.

An object of the present invention is to form a ball mill shell as a casting of iron, 15 steel or alloy metal, so shaped in cross-section as to form in contour a line not unlike saw teeth to conform substantially to the curvature of the lining plates for the purpose of accommodating the uneven surfaces 20 which for various reasons are sometimes desirable on the bottoms of liner plates.

Another object is to form a ball mill shell of cast metal having recesses through which the bolts for attaching the liner plates to 25 the shell pass and providing the liner plates with lugs to engage the recesses, the inter-engaging parts serving as a means to prevent bodily movement of the plates within the shell, thus relieving the securing bolts 30 of shearing strains set up in mills of this character, and which strains often break the bolts, thereby permitting the plates to be dislodged causing great damage to the mill and impairing the efficient operation thereof.

35 A further object is to provide a shell for ball mills so shaped as to conform to the under sides of the liner plates so that a liner plate may be used which will wear uniformly, thus reducing the amount of waste 40 usually experienced in discarding liner plates of the class included in this invention; such plates become so worn at the thin portions as to be no longer useful.

A still further object is to form a ball 45 mill shell and liner plates therefor having coöoperating lugs and recesses to prevent bodily movement of the plates within the shell by reason of engagement of the parts, thus relieving the attaching bolts from 50 shearing strains.

Generally speaking, I accomplish the above and other objects by forming a ball mill shell of cast metal in the form of conventionalized saw tooth shape in section and 55 providing a plurality of faces, the rear

edges of which are offset below the front edges of the faces, and joining adjacent faces by an abrupt wall, forming shoulders on the inside of the shell.

The present practice of ball mill construction includes a mill shell made of a flat piece of tank or boiler plate so formed as to make a cylinder. The liner plates are of cast metal and of various shapes in cross section, the purpose being when the plates 60 are in position to form an irregular surface within the mill so that as same is rotated the balls will be moved to drop on the material within the mill, thereby pulverizing the material and also serving as a means to 65 agitate the material being treated. In some instances the plates are made to have but slight contact with the inside of the shell. In such instances filler blocks are employed 70 in order that the plate may have a continuous 75 backing, which backing is necessary to support the plates against breakage. The plates used in the present style of mill are substantially wedge-shaped in cross-section, the securing means passing through the 80 thicker portion of the plate. It has been found in practice that as these plates become worn the thinner portions break, thus exposing the shell to damage by the heavy 85 balls, which are sometimes as large as five 90 inches in diameter; consequently when the plates become worn it is necessary to replace them with others. In order to provide mill liners of satisfactory size and thickness in 95 the thin portion it has been customary to 90 make the liners unnecessarily heavy at certain portions. As a consequence of this when the plate has given its maximum service the weight of the metal involved in the plate which is then discarded is much 100 greater than need be. I have overcome the above objections by employing a plate which is not much thicker at the thick end than it is at the thin end, and forming the shell of the mill as a casting making the same in a series of faces or plates to conform to the under side of the plates, and so take some of the load imparted to the liners.

My invention will be more easily understood by reference to the drawings, where- 105 in:

Figure 1 is a cross-sectional view of a portion of a plate mill shell and liner plates embodying my invention, and

Fig. 2 is a plan view of the preferred 110

form of plate, looking at the plate from the right hand of Fig. 1.

In carrying out my invention I form a plate mill shell of cast metal, a portion of the shell being shown in Fig. 1, and indicated by the reference character 5. This shell may be made as a complete cylinder, or in a series of sections which when suitably secured together form a cylinder. The shell 5 is of uniform thickness throughout except at the bosses through which the securing bolts pass. In the form shown the shell is cast in such manner as to present a series of wavelike faces not unlike modified saw teeth. The direction of rotation of the mill is indicated by the arrow in Fig. 1, the parts being arranged accordingly. Reference to the various parts will be made with respect to the direction of rotation of the mill. The cast metal shell is formed with a plurality of faces. Every face includes a front edge 7 and a rear edge 6. The portion of the faces adjacent the meeting edges 6 and 7 being substantially arcuate, with the rear portion 6 below the front edge 7 of the next succeeding face, the adjacent edges of the faces being joined by the walls 8 which are substantially radial. Near the front edges of every face, the faces are offset forming bosses 9 with corresponding depressed portions 10 in the inner surfaces of the several faces. The bosses 9 are provided with apertures 11 through which may pass bolts 12 for securing the liner plates in position in the mill. As the bosses are apertured, the same are necessarily thicker than the balance of the faces of the shell for affording strength about the apertures 11.

40 The liner plates embodying my invention are made with the under side adapted to conform to and rest on the inner surfaces of the various faces of the mill, affording complete contact and support from front to back. The thicker or front portions of the liner plates are provided with suitable apertures 13 having counter-bored portions 14 for the reception of the heads of the nuts 12, which heads are preferably enlarged and wedge-shaped in elevation, the purpose being to hold the plates securely against the shell and to properly position the same. The inner surfaces of the plates are formed with lugs 15 adapted to engage the recesses 10 formed in the bosses 9 as before described. With the plate arranged in position it is noted that the rear or following edge of the plate falls short of the shoulders formed by the radial walls 8. The rear or heel edges of the plate are upturned at 16, and are in size such as to be engaged by the overhanging rear portion of the next preceding liner plate for the purpose of holding the rear edge of the plate in position. Experience has shown

that when plates of this sort have been in service a certain length of time stretching or elongation thereof takes place. This is due to the incessant dropping of the heavy balls on the plates as the mill operates. With a plate constructed in accordance with my invention, the front or thicker portion is held securely against bodily movement with respect to the length of the shell and whatever elongation takes place in the thinner or free portion is permitted by the peculiar construction and arrangement of the plate of my invention. By stopping the rear edge of the plate short of the shoulder 8 and not bolting the same, the plate is permitted to elongate without shearing the securing bolts 12. It is to be noted that as the parts are shown in the drawings there is a slight space between the bolts 12 and the inner surfaces of the apertures in the bosses. All of the plates are of the same general shape and character so that as many plates as desirable may be made from a single set of patterns, thus reducing the cost of manufacture of the plates and making possible the carrying of fewer shapes and sizes of plates in stock by the users of ball mills.

While I have described more or less precisely the details of construction of my invention, I do not wish to be understood as limiting myself thereto, as I contemplate changes in form and the proportion of parts and the substitution of equivalents as circumstances may suggest or render expedient, without departing from the spirit of my invention.

I claim:

1. A ball mill comprising a shell of cast metal of saw-tooth construction providing a series of faces, the rear portions of the faces being offset inwardly with respect to the front portions of the adjacent faces and being integral therewith, a substantially radial wall connecting the edges of the adjacent faces, and liner plates arranged to conform to the shape of said faces and bearing against the inner surfaces thereof, said bearing being co-extensive with the width of said plates, the adjacent plates being arranged with the rear edge of the preceding plate overlying the front edge of the succeeding plate and the front edge of the plates terminating short of the shoulders formed in the shell and means for securing said plates to the shell.

2. A ball mill construction including a mill shell and liner plates therefor, said liner plates having curved surfaces for resting on the mill shell with the leading edges of the plates provided with means for securing the same to the shell, the contact between the plates and shell being co-extensive with the widths of the plates and with the following edges unrestrained and retained in po-

sition by engagement with the next succeeding plate.

3. A liner plate for ball mills having a thickened toe which is provided with holes 5 for the reception of fastening bolts, and with the heel adapted for engagement by the projecting toe of the next succeeding plate, said parts being arranged in engagement by the stepped configuration of the mill shell.

10 4. A liner plate for ball mills gradually decreasing in thickness from the toe to the heel, the toe being perforated for the reception of fastening bolts, and the heel being imperforate and provided with an upturned 15 end adapted to underlie the toe of the adjacent plate clear of the fastening means for the adjacent plate.

5. A ball mill construction including a mill shell having recesses therein and liner 20 plates therefor, said liner plates having heel and toe portions, the toe portion being thickened and being provided with a lug on its under side adapted to engage a recess in the mill shell, the toe portion having a bolt 25 opening extending through the lug, and the heel portion having an end adapted to contact the under side of the toe of the adjacent plate for retaining the heel in position.

25 6. A ball mill including a shell having a plurality of depressions formed therein, and liner plates for said mill having lugs for co- 30 operation with said depression for preventing movement of the plates relatively to the shell.

35 7. A ball mill including a shell having a plurality of depressions formed therein, liner plates for said mill having lugs for co-

operation with said depressions for preventing movement of the plates relatively to the shell, and means passing through said lugs 40 and recesses for retaining said plates in position in said shell.

8. A ball mill having its shell formed with longitudinally extending corrugations forming radial steps, and liner plates having heel and toe portions adapted to be secured to said steps, said plates being arranged with the toe portions thereof extending over the heel portions of adjacent plates. 45

9. A ball mill having its shell formed with longitudinally extending corrugations forming radial steps, liner plates having heel and toe portions adapted to be secured to said steps, said plates being arranged with the toe portions thereof extending over the heel portions of adjacent plates, and means passing through the toe portions for retaining said plates in position in said mill. 50

10. A tube mill liner plate consisting of a curved body having a thickened toe portion with an opening therein, and a lug on the under side of the plate surrounding the opening in said toe portion. 60

11. A tube mill liner plate consisting of a curved body having a thickened toe portion with an opening therein, a lug on the under side of the plate surrounding the opening in said tube portion, and means passing through said opening for securing said plate 70 in position in a mill shell.

Signed at Chicago, Illinois, this 28th day of July, 1919.

WALTER S. McKEE.
